WILLIAM KOELZER, OF AUBURN, NEBRASKA.

INTERNAL-COMBUSTION ENGINE.

1,132,357.

Specification of Letters Patent. Patented Mar. 16, 1915.

Application filed February 4, 1913. Serial No. 746,161.

To all whom it may concern:

Be it known that I, WILLIAM KOELZER, citizen of the United States, residing at Auburn, in the county of Nemaha and State of Nebraska, have invented certain new and useful Improvements in Internal-Combustion Engines, of which the following is a specification.

My invention relates to internal combustion engines and particularly to the valve mechanism thereof controlling the inlet and outlet of motive fluid to the cylinders.

The primary object of my invention is to provide an internal combustion engine with a valve mechanism which will be simple in construction, thoroughly effective in action and which shall be practically noiseless.

A further object is to so construct the valve mechanism that one sleeve valve shall control the inlet of motive fluid to all the cylinders, and in this connection to provide a sleeve valve which shall control the inlet of motive fluid to the precompression chambers of the several cylinders and the inlet of motive fluid from said precompression chambers to the several cylinders.

A further object is to provide a valve mechanism which is particularly adapted for two-cycle engines and which will permit a two-cycle engine to be throttled down and to fire regularly.

A further object is to so construct an internal combustion engine of the two-cycle type that the fresh gas shall be introduced into the cylinder at the upper end thereof in such position that the incoming fresh gas will cause the expulsion of the burned gases with only very slight danger of contamination.

A further object is to so form the head of the combustion chamber that the velocity of the gas on entering the combustion chamber will be decreased and the fresh gas will be expanded along the gradually enlarged head of the combustion chamber covering the burned charge and driving it bodily outward instead of tending as at present to churn up the burned charge and mix with it.

A further object is to provide means to prevent the precompression pistons working against a vacuum where full power is not being used or wanted.

Other objects will appear in the course of the following description.

My invention is illustrated in the accompanying drawings wherein:

Figure 1 is a vertical sectional view of an internal combustion engine constructed in accordance with my invention, the section being taken on the line 1—1 of Fig. 2. Fig. 2 is a vertical section taken on the line 2—2 of Fig. 1. Fig. 3 is a horizontal section taken on the line 3—3 of Fig. 2. Fig. 4 is a fragmentary sectional view on the line 4—4 of Fig. 2. Fig. 5 is a horizontal section on the line 5—5 of Fig. 2. Fig. 6 is a detail view of the valve 17, the parts being broken away. Fig. 7 is a section of the valve on the line 7—7 of Fig. 6. Figs. 8, 9 and 10 are fragmentary sectional views showing the position of the valve with relation to the other cylinders and the engine. Fig. 11 is a vertical sectional view through the head of a four-cycle internal combustion engine showing a modification of the valve adapted to control the inlet and exhaust of motive fluid from the combustion chamber thereof.

Corresponding and like parts are referred to in the following description and indicated in all the views of the accompanying drawings by the same reference characters.

In the drawings, A, B and C designate three cylinders of a two-cycle internal combustion engine. Each cylinder opens into a crank case 2. Each cylinder has two diameters, that is, the upper portion of each cylinder is relatively small and forms a combustion chamber 3 while the lower portion is relatively large and forms a precompression cylinder 4. Operating within each cylinder is a piston 5 having an enlarged lower end which forms a compression piston 6 coacting with the wall of the precompression chamber.

The upper portion of each cylinder is jacketed as usual and at about the middle of the cylinder is formed an annular exhaust chamber designated 7 communicating by a plurality of ports 8 with the interior of the combustion chamber. The exhaust chambers of all the cylinders communicate with a common exhaust manifold.

Disposed in the crank case 2 is a crank shaft 9 having cranks set as illustrated in Fig. 1 at angular distances of 120° and connected by piston rods 10 to the respective pistons 5. All of these parts are of any usual or desired form and their special con-

struction forms no part of my present invention.

The upper portion or head of each cylinder is circularly contracted and this contracted portion merges gradually into a laterally flared, relatively narrow port 12 which communicates with a cylindrical valve casing 13 which extends across the upper end of all the cylinders. Extending entirely along the valve casing and preferably formed integral therewith is a gas chamber designated 14 which has a port 15 leading to a carburetor or other source of gas supply. The valve chamber 13 and the gas chamber 14 are preferably formed integral with the several cylinders of the engine though not necessarily so formed.

The interior of the valve chamber 13 is cylindrical for the reception of a cylindrical sleeve valve as will be later stated, and each valve chamber is connected by means of branch ports 16^a and 16^b to a passage 16 leading to the precompression cylinders 4 of the several combustion chambers.

Disposed within and fitting snugly the interior surface of the valve casing 13 is a cylindrical sleeve valve 17. This sleeve valve is preferably constructed in two sections, one located interiorly of the other for a purpose to be later stated, but inasmuch as these sections move together, they constitute one cylindrical body forming the valve. The sleeve valve is provided with three ports for each cylinder, these ports being set equidistantly from each other and illustrated as disposed 120° apart. The sleeve valve is intended to run one-third as fast as the crank shaft or turns 120° while the crank shaft turns through a full circle. Thus each complete rotation of the crank shaft will bring one of the ports into coincidence with the port 12 leading into the combustion chamber.

Disposed interiorly of the sleeve valve is a stationary member designated generally 18. This member is hollow and is provided with a plurality of diametrically extending septa 19. Preferably each web 19 is outwardly bowed so as to form a relatively shallow gas passage designated 20. The other portion of the stationary member constitutes a gas receiving chamber and is designated 21. The gas passage 20 at its opposite ends is provided with relatively wide ports 22 and 23 leading respectively into the gas chamber 14 and into the upper end of the branch 16^a of the precompression passage 16. The gas receiving chamber 21 of the stationary member is formed with two ports arranged in quartering relation, the port 24 being coincident with the end of the branch 16^b of the precompression port 16 and the other, 25, being coincident or opposite to the port 12 leading into the combustion chamber. The sleeve valve 17 is formed as

before stated with three ports for each cylinder designated 26.

Preferably the stationary member 18 is formed integral with the valve casing but has its exterior face spaced from the interior face of the valve casing a sufficient distance to permit the sleeve valve to fit snugly between the stationary member and the valve casing and to move easily therein. As illustrated in Fig. 3, the internal or stationary member opens at its ends through the open end of the valve casing, and is connected by means of an elbow 29 to one end of the gas chamber 14. Disposed within this elbow is a hollow cylindrical rotatable by-pass valve 30 having two ports 31 and 32 so disposed that when turned in one position the port 32 will communicate with the gas chamber 14 and the port 31 with the gas receiving chamber 21, and that when turned in the other position, that is, the position shown in Fig. 4, these two ports 31 and 32 will be closed, cutting off communication between the gas receiving chamber and the gas chamber.

It will be noted from Fig. 1 that the port 12 is relatively shallow in depth and relatively long, having a length nearly equal to the largest diameter of the combustion chamber and that as this port narrows in width it gradually increases in its depth (see Fig. 2) and merges into the relatively contracted rounded portion 11 of the upper end of the cylinder, and that this rounded, contracted central portion 11 gradually flares downward and outward and merges into the full diameter of the cylinder.

It will be seen that the outwardly flaring, relatively shallow port 12 forms a pocket leading laterally outward from the upper end of the combustion chamber, and disposed in this laterally flaring pocket are one or more spark plugs designated 33 of any usual or approved construction. It will be noted that this special design of combustion head coacts with the rotary sleeve valve to take the fresh gas from an oblong port in the rotating valve and that the passage or port then increases in width and decreases in length until such passage is nearly circular in form and about one-half the full diameter of the working cylinder. The combustion head then gradually flares downward and increases in diameter until the full diameter of the working cylinder is reached. Inasmuch as the spark plug or plugs are located in the pocket formed by the port 12, and inasmuch as this port will be filled completely with fresh gas when the combustion chamber is filled with gas, the spark plug or plugs will fire even a small charge and there will be no danger of non-ignition as is the case with two-cycle engines constructed in the ordinary manner.

While I do not wish to limit myself to

the use of a sleeve valve constructed in sections, one surrounding the other, I preferably construct the sleeve valve as illustrated in Fig. 7 wherein the valve is formed of an outer shell or section designated 17^a and an inner section 17^b. These sections have a fixed relation relative to each other and both of the sections are formed with the ports 26. These shells 17^a and 17^b are longitudinally slotted or cut at intervals as at 34 to allow for the expansion of the valve. The cuts in one shell 17^a are arranged so that they do not come in line or register with the cuts in the shell 17^b. Not only do these cuts or slots 34 permit the valve to expand but they also serve to allow the lubricating oil to reach all parts of the valve and act to a certain extent as pockets to retain a small amount of lubricating oil so that the valves shall be kept well lubricated at all times.

It will be seen that the passage 20 forms a gas passage connecting the gas chamber with the suction branch 16^a of the passage 16 and that the port 16^b or branch of the passage 16 forms a discharge port through which the compressed gas from the compression cylinder passes into the gas receiving chamber 21. As before stated, the sleeve valve runs one-third as fast as the crank shaft or turns 120° while the crank shaft makes one complete circle. This being so, the action of the valve as applied to each cylinder is as follows.

Assuming that the piston of the cylinder 35 is at the upper center, the sleeve valve is just opening ports 22 and 23, the sleeve valve moving in the direction of the arrow, Fig. 8, or in the same direction as the crank shaft. The precompression piston formed by the 40 enlargement 6 of the cylinder on its out or down stroke draws in an explosive charge from the carburetor, into the gas chamber 14, then through port 22 in sleeve valve, then through the passage 20 in stationary 45 member, then through port 23 and branch 16^a into the precompression chamber 4. Just before the piston has completed its down or out stroke, the sleeve valve has closed the gas passage 20 through the stationary member and opened the port 12. As 50 the piston returns the port 12 is closed and the charge is compressed in the combustion chamber. As the port 12 is closed, the port 24 is opened by the sleeve valve, allowing 55 the precompression cylinder to discharge into the gas receiving chamber 21 and to close before the piston reaches its upper center.

The cycle of operation is the same as that 60 of any ordinary two-cycle engine, bearing in mind, however, that the cranks on the shaft are set 120° apart and the cylinders fire in the order of 1,—3,—2— that is, A,—C,—B.

Assuming that the piston of cylinder A is 65 on its down or working stroke, then the ex-

haust ports are so located that the burnt charge begins to escape at about 40° before the lower center is reached, as is the usual practice in two-cycle engines. About 30° before lower center of the crank for cylinder A, port 12 just begins to open. This cylinder is then in condition to receive its charge, thus enabling charge scavenging of the cylinder. As the cranks are set 120° apart and the cylinder B precedes cylinder 75 A 120°, if the port 12 of cylinder A opens 20° below lower center, then the piston of cylinder B will be 90° past lower center and the precompression piston will have compressed the fresh gas somewhat to this point. 80 The piston of cylinder B is on its fastest travel at this point and is charging the combustion chamber A. This same cycle is repeated with the other cylinders. The piston of cylinder B precedes the piston of cylinder A by 120° and its precompression cylinder charges cylinder A. As the piston of cylinder A precedes the piston of cylinder C by 120°, it in turn charges cylinder C. The piston of cylinder C precedes the piston of cylinder B and hence charges cylinder B, or, in other words, each working cylinder is charged by the precompression cylinder whose piston precedes the piston of the working cylinder by 120°.

While my invention may be applied to four-cycle engines as will be later stated, it is particularly applicable to two-cycle engines. These engines as at present constructed fire irregularly when burning a small charge. As the incoming charge is deflected by the baffle plate carried by the piston into the combustion chamber, it mingles with the burned gases that are not expelled and a small charge will be either lost in the 100 gases that are not expelled or be too much polluted with burned gases to ignite. The next following charge contains less burned gas, it is true, and the charge will ignite but these conditions cause irregular running on low throttle. Furthermore in rapid running of two-cycle engines, the cylinder is liable to become rapidly choked up with exhaust gas products which are unable to escape when high speeds are attempted and hence the two-cycle engine has not been used for high speeds.

With the revolving sleeve valve arranged as heretofore described, the charge enters the extreme upper end of the combustion chamber. If the charge is small, some will mingle with the burned gases, but the port 12 leading from the valve chamber while very short will be filled with fresh gas and as the spark plug or plugs are disposed in this port even a small charge will be fired with certainty.

Ordinarily two-cycle engines are built with a larger bore than stroke to get rid of the burned gases. The inlet port is on one side of the cylinder and the exhaust on the 120

opposite side. The fresh charge is supposed to be deflected up to the head of the combustion chamber, be deflected downward thereby, strike the burned gases and drive them out. As a matter of fact, in the ordinary form of two-cycle engine, the fresh gas enters the burned charge almost as a wedge and pushes the burned gases along for nearly twice the length of the combustion chamber. It will therefore mingle with the burned gases to a great extent. With my invention, the engine can be built with a long stroke and small bore or vice versa, if desired. By using a long stroke and a small bore and having an exhaust port running entirely around the cylinder to release the burned gases evenly from the space above the piston, the fresh gas entering at the end of the combustion chamber will push the burned gas along instead of churning it up as does the fresh gas entering at one side of the cylinder which passes up the cylinder and returns on the other side to the exhaust port. Furthermore instead of having a baffle plate upon the piston, the piston is entirely free from all projections of any kind. All precompression cylinder engines take in a full charge of gas at all times and discharge the gas into a gas receiver. If full power is not wanted, these pistons work against a vacuum. By providing a by-pass leading from the rotary valve into the gas chamber, part of the charge where full power is not wanted is allowed to escape into the gas chamber, thus preventing the precompression pistons from working against a vacuum.

With my rotary sleeve valve, the ports can be so timed as to give the fresh gas more time to fill the combustion chamber and by increasing the size of the precompression cylinder so as to pump a larger volume of gas than will fill the content of the working cylinder or combustion chamber, a full cylinder of fresh gas will be the result.

While I have shown the ports on the rotary valve as spaced from each other an angular distance of 120° , these ports might be spaced at 90° but in this case the crank shaft would make four revolutions to one of the sleeve valve instead of three revolutions to one of the sleeve. The success of this rotary sleeve valve as a means for causing the proper discharge of burned gases and the proper filling of the combustion chamber with fresh gases depends upon the proper design of the combustion chamber head. If the port 12 were oblong, the fresh gas would have quite a high velocity and would pierce the burned charge, churn it up and mingle with it instead of driving it out. By my construction, the port is given such form that it gradually decreases in length and increases in width until it is a circular opening and this merges into the full diameter.

of the cylinder by a downwardly flaring wall. Hence the fresh gas on entering will decrease in velocity and expand along the gradually enlarging head and cover the burned charge, driving it out instead of piercing and commingling with it.

With slight modifications of ports, the sleeve valve can be applied to four-cycle internal combustion engines having any number of cylinders, one sleeve valve serving for all the cylinders. If there was a six cylinder engine the sleeve would be timed to make one complete revolution to six complete revolutions of the crank shaft, that is, the sleeve would turn 60° to one revolution of the crank shaft. Such a valve is illustrated in Fig. 11 wherein 35 designates the combustion chamber of a four-cycle internal combustion engine surrounded by the usual water jacket 36. Extending across the heads of all the cylinders is a cylindrical valve casing 37 having a smooth internal surface and opening into each cylinder by means of ports 38 and 39. Extending longitudinally parallel to the valve casing and preferably formed integral therewith is an exhaust manifold 40 which opens by a port 41 into the interior of the valve casing. Extending parallel to the exhaust manifold 40 and extending across the heads of all the cylinders is an intake manifold 42 opening by a port 43 into the interior of the valve casing.

Disposed within the valve casing and rotatably mounted therein is a sleeve valve 44 formed with three ports, 45, 46 and 47, adapted to coact respectively with the ports 38, 39, 41 and 43. Located within the sleeve valve is the fixed or non-rotatable member 48 cored to provide an exhaust passage 49 extending from the port 41 to the port 38 and a suction gas passage 50 extending from the port 43 to the port 39. The space between the walls of these passages 49 and 50 is cored out to form cold water spaces 110 or chambers communicating with the water cooling system of the engine. The action of this valve is as follows.

Assuming that a charge has been fired and is ready to be exhausted, the exhaust ports 38 and 41 are about to open as the piston is about 30° above its lower center. The ports being about 18° in angular length, opening and closing would cause the sleeve to travel 36° . The crank shaft travels six times as fast as the sleeve valve and the exhaust will be open 216° on the crank shaft. The piston will then be about 5° past upper center. 10° later the suction ports 39 and 43 each open allowing the piston to draw gas from the carburetor from the intake manifold 42 into port 43, then through the passage 50, then through port 39 into the combustion chamber. The ports will close when the piston is about 30° past

lower center. All ports will then be closed approximately 290° . It will be understood that the periods given above through which the ports remain open and close is approximate but that the statements are substantially correct.

While I do not wish to limit myself to any particular means for driving the continuously rotating sleeve valve, I have illustrated in Fig. 1 the sleeve valve as being driven by means of a sprocket wheel 51 fast upon a prolongation of the rotary valve, this sprocket wheel being connected by means of a sprocket chain 52 to a sprocket wheel 53 mounted upon the crank shaft 9. It will be obvious that by changing the ratio of the small sprocket wheel to the large, the rate of rotation of the valve will be changed.

In Figs. 1 and 3 I have illustrated a special means for attaching the sprocket wheel to the valve. In Fig. 3, 53 designates an enlargement or extension of the valve chamber within which the rotary sleeve valve 17 projects. Within the projecting end of the valve 17 is disposed a split expanding sleeve 54 and within this expanding ring or sleeve is an expansion plug 55. Disposed on the exterior of the valve sleeve 17 is a driving ring designated 56 which extends out beyond the extension 53 of the valve casing and is formed with radially projecting, oppositely disposed arms 57. The sprocket wheel 51 is mounted in ball bearings upon the extension of the valve casing and is connected to the arms 57 by means of pivot links 58. Pins 59 lock valve 17 to the driving ring. This construction provides a means of driving the valve so that there shall be no side pull on the valve, and while I do not wish to be limited to it, it is a preferable construction.

While I have illustrated what I believe to be the best form of my invention, it is understood that many modifications might be made without departing from the spirit of the invention.

What I claim is:

1. In an internal combustion engine, the combination with a combustion chamber having an inlet port at its closed end, of a valve casing into which said port opens, said valve casing being connected to a source of fuel and a pre-compression chamber, a fixed member disposed within the valve casing and divided into two passages by a septum, each passage ending in a port registering with the ports of the exterior wall of the valve casing, and a rotatable valve disposed between the fixed member and the valve casing and controlling said ports.

2. In an internal combustion engine, the combination with a combustion chamber having an inlet port at its closed end, of a valve casing into which said port opens,

said valve casing being connected to a source of fuel, and a pre-compression chamber having two ports communicating with the interior of the valve casing, a fixed member disposed within the valve casing 70 and divided into two passages by a septum, each passage ending in a port registering with the ports of the exterior wall of the valve casing, leading respectively into the gas chamber and the pre-compression chamber, and a rotatable valve disposed between the fixed member and the valve casing and controlling said ports.

3. In an internal combustion engine, a two-diametered cylinder having an inlet 80 port at one end, a piston operating in the cylinder and having an enlarged head operating in the portion of the cylinder having the largest diameter, this portion of the cylinder constituting a pre-compression chamber, a cylindrical valve casing disposed at the opposite end of the cylinder, a gas chamber, a fixed interior member disposed within the valve casing and divided by a septum into two passages, the valve casing 85 having an inlet port to the cylinder opening into one of said passages and the port in the same passage opening to the pre-compression chamber, the opposite passage having a port opening into the pre-compression chamber and into the gas-chamber, and a rotatable valve disposed between the fixed chamber and the valve casing and having ports controlling said passages.

4. In an internal combustion chamber, the combination with a plurality of combustion chambers, and a plurality of compression chambers, one for each chamber, each combustion chamber having an inlet port, of a hollow tubular valve co-acting with all of the chambers, a gas chamber, said valve having ports co-acting with the inlet port of each combustion chamber, and ports adapted to permit the entrance of fuel from the gas chamber into the interior of the valve and thence intermittently into the pre-compression chamber, and means for permitting part of the charge in the valve to escape back into the gas chamber.

5. In an internal combustion engine, the combination with a plurality of combustion chambers, each having an inlet port at its closed end and a plurality of pre-compression chambers coacting therewith, of a tubular valve casing coacting with all of the cylinders with the interior of which the inlet ports of the several combustion chambers communicate, said valve chamber having ports opening into the several combustion chambers, into the several pre-compression chambers, and into the gas chamber, an interior fixed member disposed within and concentric to the valve casing and having like ports, said member being divided into two passages by a transverse septum, one of said 125

- 6
 1. **passages being adapted to establish communication between the gas chamber and the pre-compression chambers and the other being adapted to establish communication between the combustion chambers and the several pre-compression chambers, and a hollow cylindrical and rotatable valve disposed in the valve chamber, and extending along its entire length, said valve having ports adapted to register with the ports of the valve chamber, and means for rotating the valve continuously in one direction.**
- 5 **6. In an internal combustion engine, the combination with a combustion chamber, closed at one end and the opposite end being formed to provide a precompression chamber and a two-diameter piston coacting with the combustion chamber and the pre-compression chamber, of a valve casing disposed at the closed end of the combustion chamber and communicating therewith by a port, said precompression chamber communicating with the valve casing by a passage having branched ports, a gas chamber having a port opening into the valve chamber, a cylindrical rotatable hollow valve disposed within the valve chamber and having a plurality of ports adapted to register with the several ports of the valve chamber, and an internal stationary member disposed within the rotatable valve, divided into a gas passage and a gas receiving chamber, the gas passage at its opposite ends being adapted to register with one of the branches of the precompression passage and with the port leading to the gas chamber and the gas receiving chamber having ports registering, one with the port leading to the combustion chamber and the other with the other branch port of the precompression, and means for rotating said valve to establish communication between the gas chamber and the pre-compression chamber, between the gas receiving chamber and the precompression chamber and between said gas receiving chamber and the combustion chamber.**
- 10 **7. In an internal combustion engine, the combination with a plurality of combustion chambers, each closed at one end and enlarged at its opposite end to form a precompression space, a two-diameter piston for each combustion chamber and coacting with the combustion chamber and the precompression space, a valve chamber coacting with all of said combustion chambers and disposed adjacent the closed ends thereof, each combustion chamber having a port opening into the valve chamber, each pre-compression chamber having a passage leading toward the valve chamber and terminating in two branches opening thereinto, a gas chamber having a port opening into the valve chamber, a hollow rotatable valve extending the full length of the valve chamber**
- 15 **and formed with ports adapted to coact with the ports thereof, means for rotating said valve continuously in one direction, and an internal stationary member disposed within the rotatable valve and divided by a transverse web into a gas receiving chamber extending along the full extent of the valve, and a gas passage, the gas passage having ports opening at its opposite ends into the gas chamber and into one of the branch ports of each precompression passage, the gas receiving chamber having ports registering, one with the inlet port of each combustion chamber, and ports registering with the other of the branch passages of each precompression passage.**
- 20 **8. In an internal combustion engine, the combination with a plurality of cylinders, each formed at its lower end to form a pre-compression chamber and double diameter pistons operating, one in each cylinder and coacting with the precompression chamber thereof, of a gas chamber common to all of the cylinders and adapted to be connected to the carburetor of the engine, a gas receiving chamber communicating with the several cylinders, and a valve adapted in one position to cut off communication between the gas receiving chamber and any one of the cylinders and establish communication between the gas chamber and any one of the precompression chambers, and in another position to cut off communication between the gas chamber and any one of the precompression chambers and establish communication between the gas receiving chamber and any one of the cylinders.**
- 25 **9. In an internal combustion engine, a combustion chamber enlarged at its lower end to form a precompression chamber, a two-diameter piston operating in the combustion chamber and coacting with the pre-compression chamber, a gas chamber adapted to be connected to the carburetor of the engine, a hollow rotary valve having ports adapted to establish communication between said gas chamber and the precompression chamber, and between said compression chamber and the interior of the valve, and between the interior of the valve and the inlet port of the combustion chamber, a by-pass opening at one end into the hollow valve and at its other end opening into the gas chamber, and a valve for controlling the passage of fluid through said by-pass.**
- 30 **10. In an internal combustion engine, the combination with a plurality of combustion chambers and a plurality of precompression chambers, one for each combustion chamber, each combustion chamber having an inlet port, of a hollow tubular valve coacting with all of the chambers, a gas chamber common to all of the combustion chambers, said valve having ports coacting with the inlet port of**

each combustion chamber, ports adapted to permit the entrance of fuel from the gas chamber into the interior of the valve and ports adapted to permit the passage of fuel 5 to and from the precompression chambers, and a valved by-pass connecting one end of the gas chamber with one end of the rotary valve whereby to permit part of the charge

in the valve to escape back into the gas chamber. 10

In testimony whereof I affix my signature in presence of two witnesses.
